UNITED STATES PATENT OFFICE.

LELAND G. FAIRBANK, OF SAN FRANCISCO, CALIFORNIA.

WAVE MOTOR.

Original application filed November 27, 1923, Serial No. 677,299. Divided and this application filed August 24, 1925. Serial No. 52,242.

This invention relates to propellers adapted to generate power from the force of running water or of waves washing back and forth, and is in fact a division of my application for patent on wave motor, filed November 27, 1923 under Serial Number 677,299.

The principal objects of the herein described invention are to provide an automatically reversible propeller of simple rugged construction, also such a propeller especially adapted for the wave motor described in my other application aforesaid, and of such detailed construction as will reduce the cost of its production and adapt it to a gang assemblage of great rigidity.

I accomplish the above objects by the propeller and mounting construction shown in the accompanying drawings, and in which:

20 Figure 1 is a plan view of my propeller; Figure 2 is an edge view of a portion thereof;

Figure 3 is a detached view of one of the curved stop rods for the blades;

25 Figure 4 is a side view of Figure 3;

Figure 5 is an enlarged fragment of the propeller hub with a portion in section showing the inner construction;

30 Figure 6 is an edge view of a portion of Figure 5;

Figure 7 shows the hub without blades but connected to opposite runs of the hollow shaft;

35 Figure 8 is a reduced size side view showing a gang assemblage of four propellers connected to a central gear box; and

Figure 9 is an enlarged sectional detail of the outer end of one of the propeller spokes showing it attached to the rim of the propeller.

In further detail my propeller comprises a hub 1 preferably of a hollow ring shape as shown in Figure 1, and a series of radially arranged spokes 2 secured to the rim of the hub at their inner ends and to a flat metal built up or sectional ring 3 at their outer ends, while freely pivoted to swing on these spokes are the propeller blades 4.

The blades are flat and held in place by 50 brackets 5, 6 and 7 riveted to the blades and provided with separable caps 5', 6' and 7' and internally with rust proof liners or bearings as later described.

The spokes 2 are of pipe threaded at both 55 ends and at the outer end of each is a pipe

flange 8 screwed in place and in turn riveted or bolted at 9 to the ends of the curved sections forming the outer ring 3.

At the inner end the pipe spokes screw directly into bosses 10 after first passing 60 through a steadyng boss 11 (see Figure 5).

The brackets 5 are counterbored at the outer ends to receive each a bronze bushing 12 pressed into place and having a flange 12' forming an end bearing for the bracket 65 5, while above the flange the bushing forms a fixed pivot for a split babbitt bearing 13 within the bracket. The bearings in the other brackets 6 and 7 are substantially similar to the one described, thus overcoming the 70 danger of rust at the bearings, an important point since they cannot be lubricated in the salt water submerged work for which they are intended.

The blades as so far described hang for 75 free pivotal movement upon the spokes so that they can swing either way, depending on the direction or changing directions of water in which wave motors are used, and the movement of the blades is limited by 80 stopping means at both ends.

The outer stopping means comprises a series of curved bars 14 forming a flat concentric ring when viewed in plan as 85 shown in Figure 1 and of saw tooth arrangement when viewed edgewise of the propeller, as indicated in Figure 2.

The edge and flat sides of these bars are indicated respectively in Figures 3 and 4 and they are arranged in oppositely diverging 90 relation on opposite sides of the propeller so as to form limit stops for the propeller blades in both directions of swinging of the same as indicated in Figure 2.

These bars are bolted at their ends to 95 cross arms 15 in turn secured to flanges 16 surrounding the spokes.

The blades swing outwardly to either side of the propeller until they encounter the bars 14 which form a stopping contact entirely across the width of the blades.

The inner or hub ends of the blades are also stopped at the limit of the swinging movement of the blades by lugs 17 formed on opposite sides of bearing brackets 5, and which lugs respectively meet opposing lugs 18 formed on opposite sides of the hub, thus when the blades swing over to the desired limit of their travel in either direction 105 they are held absolutely firm at the re- 110

quired pitch by bars at the outer ends and lugs at the inner ends.

To provide for rigid gang mounting of several propellers the hub is hollow with a 5 circular row of bolt bosses 19 and with opposite sides of the hub provided with aligning flange members 20 adapted to seat against complementary surfaces of pipe flanges 21 and to which flanges sections of 10 large pipe 22 are screwed as well as welded or pinned so as to form a hollow shaft extending from one propeller to the next, the pipe flanges 21 being bolted to the hub by bolts 23 passing through both flanges and 15 hub.

Figure 8 shows such an assemblage with four propellers in place and at the extreme ends of the shaft 22 are flanges 21' to which are bolted flanges 22' carrying bearing 20 tensions 24 of a lesser diameter than the large hollow shaft, and when used with the wave motor of my former application, I provide similar reduced bearing portions 25 midway the length of the shaft and extend them into a gear box 26 through stuffing 25 boxes 27.

Within the gear box 26 the reduced shaft portions 25 are geared in any conventional manner, not shown, to a right angle shaft 28 extending out of the gear box through a stuffing box 29 so as to provide, when the gear propeller is submerged and suitably supported for rotation, a vertically extending power shaft available above the surface 35 of the water.

My invention as above described, while devised with especial reference to my wave motor mentioned, is not necessarily limited to such specific use, and I therefore claim 40 the construction as follows.

I claim:

1. In a device of the character described 45 propelling means comprising a shaft, rods radially extending therefrom, propeller blades pivoted to said rods and means for limiting the angle of swinging motion allowing the blades to automatically assume operative position responsive to the direction of flow of a driving medium and comprising stopping members extending from 50

the radial rod of each blade at an angle to the plane of the rods on opposite sides of the same, and cross arms associated with the next succeeding blade connecting the ends of the stopping members. 55

2. In a propeller of the character described, a hub, round spokes screwed into the hub, propeller blades pivoted to said spokes and a guiding device on the hub for each spoke at a point outward from its 60 threaded engagement with the hub.

3. In a propeller of the character described, propeller blades, a hub supporting the propeller blades, said hub having flange aligning devices on opposite sides thereof 65 and provided with means for bolting it to complementary flanges.

4. In a propeller of the character described, propeller blades, a hub having radial spokes supporting the propeller blades 70 with freedom for pivotal movement thereon and cooperating stopping means on the blades and hub adapted to limit said pivotal movement.

5. In a propeller of the character described, propeller blades, a hub having radial spokes supporting the propeller blades with freedom for pivotal movement thereon, 75 cooperating stopping means on the blades and hub adapted to limit said pivotal movement, and further stopping means active against the outer portions of the blades. 80

6. In a propeller of the character described, propeller blades, a hub having radial spokes supporting the propeller blades 85 with freedom for pivotal movement thereon, and stopping means for limiting the pivotal movement of the blades active against the face of the blades, said means comprising ring sections extending from spoke to spoke. 90

7. In a propeller of the character described, propeller blades, a hub having radial spokes supporting the propeller blades for swinging movement thereon, flanges at 95 the outer ends of the spokes and curved plate sections secured to and extending from flange to flange, said sections forming a complete ring around the propeller.

LELAND G. FAIRBANK.
